US00D823949S

(12) **United States Design Patent** (10) **Patent No.:** **US D823,949 S**
Lu (45) **Date of Patent:** **** Jul. 24, 2018**

(54) **REMOTE CONTROL**

(71) Applicant: **Shenzhen Jitian Innovation Technology Co., Ltd.**, Shenzhen, Guangdong (CN)

(72) Inventor: **Fengwen Lu**, Guangzhou (CN)

(73) Assignee: **SHENZHEN JITIAN INNOVATION TECHNOLOGY CO., LTD.**, Shenzhen, Guangdong (CN)

(**) Term: **15 Years**

(21) Appl. No.: **29/613,179**

(22) Filed: **Aug. 8, 2017**

(30) **Foreign Application Priority Data**

May 16, 2017 (CN) 2017 3 0179030

(51) **LOC (11) Cl.** **21-01**

(52) **U.S. Cl.**

USPC **D21/566**

(58) **Field of Classification Search**

USPC D13/168; D14/195, 218; D21/561, 566;

D12/174, 345

CPC A63F 13/06; A63H 30/04; G08C 17/02;

G08C 23/04

See application file for complete search history.

(57) **CLAIM**

The ornamental design for a remote control, as shown and described.

DESCRIPTION

FIG. 1 is a front view of a remote control showing the new design;

FIG. 2 is a rear view thereof;

FIG. 3 is a left side elevational view thereof;

FIG. 4 is a right side elevational view thereof;

FIG. 5 is a top view thereof;

FIG. 6 is a bottom view thereof; and,

FIG. 7 is a perspective view thereof.

1 Claim, 7 Drawing Sheets

FIG. 1

FIG. 2

FIG. 3

FIG. 4

FIG. 5

FIG. 6

FIG. 7
